UNITED STATES PATENT OFFICE

2,237,089

COMPUTING MACHINE

Edgar Ellsworth Phinney, West Orange, N. J., assignor to Defiance Manufacturing Corporation, Orange, N. J., a corporation of New York

Application October 16, 1937, Serial No. 169,413

1 Claim. (Cl. 235—60)

The invention has relation to computing machines, and particularly to control means therefore whereby one or more accumulators may be set for plus, minus or non-add operation, or whereby other operations of the machine may be controlled in accordance with the tabulated position of the carriage. Such a machine is shown in United States Patent No. 1,946,572, issued on February 13, 1934, to Loring P. Crosman. The invention consists in the novel construction and combination of parts as set forth in the appended claim.

In the accompanying drawings, illustrating the invention:

Fig. 1 is a vertical section taken through a computing machine constructed in accordance with the invention.

Fig. 2 is a rear elevation of a portion of the connections between the platen carriage and the index tube.

Fig. 3 is a front elevation of a cam plate fixed upon the carriage.

Fig. 4 is a longitudinal section through the index tube and associated parts.

Fig. 5 is a rear elevation of the yieldable driving connections for the index tube.

Fig. 6 is a projection of the index tube.

Fig. 7 is a detail transverse section through the index tube and associated parts.

Fig. 8 is a left side elevation of the means for operating the index tube feelers.

Fig. 9 is a left side elevation of the computing machine, with the casing removed and parts broken away.

Fig. 10 is a detail right side elevation of the accumulator control devices.

The setting levers 9 of the lister are provided with segments 16 (Fig. 1), adapted to engage the pinions related to the numeral wheels of accumulators 15, the shafts of these accumulators being adjustable to hold the pinions in or out of mesh with the segments during the various operations of the machine.

In order to provide for a considerable number of accumulators, segments 16 have each a roller 148 engaging a slot formed in a rack 149, having pin and slot support from the machine frame, the series of racks being engageable by any one or more of a series of additional accumulators 150. The shafts of these accumulators are as shown 50 adjusted to hold the numeral wheel pinions out of mesh with the racks.

It will be obvious, that during the rocking of the main reciprocating shaft 6 of the machine, segments 16 and racks 149 will be reciprocated, and 55

if any one of the accumulators 15 or 150 are thrown into mesh during the outward stroke of the levers 9 the numeral wheels will be rotated in a subtractive direction to an extent governed by the movement of stops 11 into contact with the depressed keys. On the other hand, if the accumulators are thrown into mesh during the return movement of levers 9, the accumulator wheels will be rotated in an additive direction, to an extent also governed by the position of the stops 11.

The selection of the accumulators to be operated and the determination of plus or minus registration thereon is effected by means of the index tube 107, this tube being rotated by an operating connection with the record carriage to bring variably indexed portions of its surface into active position.

A rail 151 (Figs. 2 and 3) is fixed upon the 20 record carriage, and one edge of this rail is provided with a series of cam steps adapted in the movement of the carriage to displace a roller 152 mounted upon a segment arm 153, which is pivotally supported at 154 upon the framing of the machine. The segment teeth of arm 153 mesh with a pinion 155 (Figs. 2, 4 and 5), and a plate 156, fast with said pinion carries thereon a spring tensioned roller 157, adapted normally to seat at the low point of a cam 158. Rotation of pinion 155, during the carriage movement will therefore rotate the cam 158, and this cam has operative connection, through an arm 159 with shaft 160, supporting and normally rigid with the index tube 107.

The cam and spring roller connection forms a yieldable drive, so that should the record carriage be accidentally moved during the time that one of the feelers now to be described are in engagement with the tube, roller 157 may be carried around the periphery of cam 158. Following such displacement of the roller 157, removal of the feeler from engagement with tube 107 will allow the roller, through spring action upon the cam, to rotate the tube into its correct relation with the record carriage.

Tube 107 extends at right angles to the shafts 200 of the accumulator wheels 150, in proximity to the left hand ends thereof, and for each accumulator there is provided two feelers 201 (Figs. 6, 7 and 8), having noses adapted to move into slots 202 of the tube. Each feeler is provided with a pivot rod 203, supported at its free end in the perforation of a bar 204, lying parallel to the tube 107.

Rocking movement of a feeler 201, to bring its

nose into the slot 202 of the index tube, will carry its rod 203 toward the left, in Fig. 7, into position above the offset end of a rack 205 or 206 (Fig. 9). Racks 205 and 206 mesh with the teeth upon opposite sides of a pinion 207, having universal joint connection 208 with one of the shafts 200. The two feelers 201 related to each accumulator are intended to rotate the accumulator shaft in one or the other direction, by means of the racks 205, 206, in order to set the accumulator for plus or minus registration.

This is effected by means of collar cams 209 (Figs. 7 and 10), fast upon shafts 200 and cooperating with reciprocating cam slides 210, 211.

Slides 210, 211 are reciprocated at the end of the stroke of settling levers 9 in each direction, by means of a two fingered plate 212, fast upon shaft 6 and adapted to operate an arm 213, connected by link 214 with the cam slides 210, 211. The high points of the cams of slides 210 are in line with the low point of the cams of slides 211, and the collar cams 209 have two distinct cam portions, one adapted to register with the slide 210 and the other with the slide 211, the high points of these two cam portions of collar 209 being radially offset from each other.

The arrangement is such that normally the low points of both portions of the collar cams 209 are opposite the slides 210, 211, rotation of shaft 200 in one direction bringing a low point of the collar cam opposite slide 210 and a high point thereof opposite slide 211, and reverse rotation of shaft 200 bringing a high point of the collar cam opposite slide 210 and a low point opposite slide 211. Slide 210 will have its high points opposite the collar cams during the return movement of the setting levers 9, and slide 211 will have its high points opposite collar cams during the outward reciprocation of levers 9, so that the rotative setting of the shafts 200 will have the effect of bringing a high point of the collar cam into engagement with a high point of one of the slides during the forward or return reciprocation of the parts, according to the direction in which the shaft 200 has been rotated. This engagement of the high point of a collar cam with the high point of a slide serves to move the shaft 200 toward the racks 149, so that the pinions of the accumulator wheels will be meshed and rotated additively or subtractively.

It is to be understood that the collar cams 209 and slides 210, 211 are duplicated at the opposite ends of the shafts 200.

The accumulators 15 are similarly set by rotation of the register shafts through pinions 215 (Fig. 9), which correspond in their action with pinions 207 of the accumulators 150. The pinions 215 are connected each with one of the racks 206 by means of racks 216, bell crank levers 217 and links 218. The system of collar cams and cam slides for the accumulators 15 are closely similar to those of the accumulators 150, and are further shown and described in the patent hereinbefore referred to.

Power for setting the accumulators to positive or negative registering condition, in accordance with the feelers 201 which are engaged with the slots 202 of the index tube, is furnished through an operating connection between shaft 6 and the bar 204. Fast upon shaft 6 is a plate 219 (Fig. 9) having a cam surface 220, normally engaging a roller carried by a U-shaped lever 221, fulcrumed at 222, upon the framing of the machine. Clockwise rocking movement of shaft 6 will cause the cam surface 220 of plate 219 to move lever 221

clockwise about point 222, depressing the free end of the lever and carrying therewith a link 223, pivoted to lever 221 at its upper end and having a perforation at its lower end engaging a pin 224, fixed in a bail 225 (Figs. 7-9) which carries the bar 204. Depression of the free end of lever 221 therefore will rock bail 225 and depress bar 204, thereby imparting pivotal movement to the rods 203 and causing any of said rods which are in projected position to operate the related rack 205 or 206 to set the related accumulator shafts. The roller of lever 221 will now leave cam surface 220 and the bar 204 will remain in depressed position until the return stroke of cam 219, just before the end of the cycle of operation, when said cam will restore lever 221. At the end of a cycle of operation of the machine the feelers 201 will be retracted, out of engagement with the slots 202 of index tube 107 as follows:

Feelers 201 are normally held in inoperative position by means of a bail 226 (Figs. 7 and 8) pivoted upon the shaft 227 which supports the feelers 201. Bail 226 is held against shoulders 228 of the feelers by means of an arm 229 pivoted at 230 upon the framing of the machine and having link connection 231 with the bail 226. Arm 229 carries a pivoted latch 232 normally engaging a roller 233 on arm 234. Arm 234 is supported on a roller 235 of the arm 112 reciprocated by shaft 6, this train of parts serving to hold the feelers 201 in retracted position against the tension of their springs 236. Upon depression of operation key 48 and counter-clockwise movement of clutch control lever 50, as viewed in Fig. 9, an arm 237, fast with lever 50 will also be rocked in counter-clockwise direction acting, through bell crank lever 238 and trigger 239 to move the latch pawl 232 out of engagement with roller 233, whereupon the feeler springs 236 will rock bail 226 clockwise as viewed in Fig. 8, pulling arm 229 and latch pawl 232 downward.

Rocking movement of shaft 6 will now carry the roller 235 of arm 112 out of engagement with the arm 234, whereupon spring 240 will rotate arm 234, bringing roller 233 again below the shoulder of latch pawl 232. During the return movement of shaft 6, roller 235 will encounter the end of arm 234, camming said arm upwardly, and bringing the parts into their original position and thereby lifting the feelers 201 out of the notches 202 of tube 107.

The index tube 107 is so mounted that it may readily be removed from the machine, and replaced by a tube calling for a different succession of operations. Therefore tube 107 is supported upon collars 241 (Fig. 4) of the shaft 160, the rear end of shaft 160 being supported in bearings 242 and the forward end being supported by engagement of the tube with bearings 243. A spring latch 244 pivoted between jaws of the collar 241 upon the end of shaft 160, is adapted to engage a slot in the forward end of tube 107, whereby the shaft and tube will rotate in unison. To remove the tube 107 from the machine, latch 244 is rocked out of engagement with the slot of the tube, and the tube is then pulled out of the machine. The new tube is engaged over the finger piece of latch 244 and is seated upon the forward collar 241, and thereafter guided into the bearing 243 and pushed into fully inserted position, in which latch 244 will reengage the slot of the tube, thus locating the tube properly both in endwise movable position and angularly rotative position.

I claim:

In a computing machine having an accumula-

tor, value entering devices, and operating means; the combination of means for setting the accumulator for positive or negative registration, including an adjustable positive setting element, an adjustable negative setting element, a device movable by said operating means, a feeler having a pivoted connector element and displaceable to connect the positive setting element with the

movable device, a feeder having a pivoted connector element and displaceable to connect the negative setting element with the movable device, and an index member adjustable to bring variably indexed portions of said member into the path of movement of one or the other of said feelers.

EDGAR E. PHINNEY.

CERTIFICATE OF CORRECTION.

Patent No. 2,237,089.

April 1, 1941.

EDGAR ELLSWORTH PHINNEY.

It is hereby certified that error appears in the printed specification of the above numbered patent requiring correction as follows: Page 3, second column, line 1, in the claim, for the word "feeder" read --feeler--; and that the said Letters Patent should be read with this correction therein that the same may conform to the record of the case in the Patent Office.

Signed and sealed this 6th day of May, A. D. 1941.
